DESCRIPTION

FIG. 1 is a perspective view of a first exemplary embodiment of a tray system showing our new design. FIG. 2 is an exploded perspective view of the tray system of FIG. 1. FIG. 3 is an exploded left elevation view of the tray system of FIG. 1, the exploded right elevation view is a mirror image.

CLAIM

The ornamental design for a tray system, as shown and described.

FIG. 4 is an exploded front elevation view of the tray system of FIG. 1, the exploded rear elevation view is a mirror image.

FIG. 5 is an exploded top plan view of the tray system of FIG. 1.

FIG. 6 is an exploded bottom plan view of the tray system of FIG. 1.

FIG. 7 is an exploded plan view of the tray system of FIG. 1 shown in an unfolded configuration.

FIG. 8 is a perspective view of a second exemplary embodiment of a tray system showing our new design.

FIG. 9 is an exploded perspective view of the tray system of FIG. 8.

FIG. 10 is an exploded left elevation view of the tray system of FIG. 8, the exploded right elevation view is a mirror image.

FIG. 11 is an exploded front elevation view of the tray system of FIG. 8, the exploded rear elevation view is a mirror image.

FIG. 12 is an exploded top plan view of the tray system of FIG. 8.

FIG. 13 is an exploded bottom plan view of the tray system of FIG. 8.

FIG. 14 is an exploded plan view of the tray system of FIG. 8 shown in an unfolded configuration.

FIG. 15 is a perspective view of a third exemplary embodiment of a tray system showing our new design.

FIG. 16 is an exploded perspective view of the tray system of FIG. 15.

FIG. 17 is an exploded left elevation view of the tray system of FIG. 15, the exploded right elevation view is a mirror image.

FIG. 18 is an exploded front elevation view of the tray system of FIG. 15, the exploded rear elevation view is a mirror image.

FIG. 19 is an exploded top plan view of the tray system of FIG. 15.

FIG. 20 is an exploded bottom plan view of the tray system of FIG. 15; and,

FIG. 21 is an exploded plan view of the tray system of FIG. 15 shown in an unfolded configuration.
